UNITED STATES PATENT OFFICE.

CHARLES C. RUPRECHT, OF MIDWAY, FLORIDA.

SEPARATING APPARATUS.

1,291,170.

Specification of Letters Patent. Patented Jan. 14, 1919.

Application filed March 31, 1917. Serial No. 158,783.

To all whom it may concern:

Be it known that I, CHARLES C. RUPRECHT, a citizen of the United States, residing at Midway, in the county of Gadsden and State 5 of Florida, have invented a certain new and useful Improvement in Separating Apparatus, of which the following is a full, clear, and exact description, reference being had to the accompanying drawings.

10 This invention relates to apparatus for separating granular material into various grades, and it has for its objects the provision of apparatus of this character wherein the screen frame is suspended, preferably 15 upon springs, so as to operate with extreme ease, obviating the use of frictionally engaging elements between the frame and its support, and doing away with numerous mechanical elements and movements common 20 to prevailing types of separating or grading apparatus; the provision of apparatus of the aforesaid character involving an actuating element having no physical operative connection with the screen frame yet capable 25 of exerting a moving influence thereon; the provision of apparatus of the above character permitting of adjustment of either or both the periods of vibration of the screen and the intervals of effectiveness of the actuating element whereby various degrees and 30 timing of vibrations may be obtained; the provision of a separating apparatus affording easy removal and replacement of the screen frames, for the purpose of repair or 35 the substitution of screen frames, without the need of disturbing any of the adjustments or parts of the apparatus; the provision of an apparatus of the aforesaid character having operating parts immune from 40 injury or hindrance by the dust and grit in the presence of which the apparatus is required to operate; and the provision of apparatus of the foregoing character wherein but very few of the operating parts demand 45 lubrication and attention.

A further object is to impart to the screen a movement conducive of the highest separating efficiency, such movement effecting a sequence of conditions wherein, first the 50 screen is quiet and the material gravitates downward at a rate dependent upon the

weight of material and degree of inclination of the screen; second, the screen is quickly withdrawn from the material leaving it suspended in the air, the present movement of 55 the screen terminating in a quick "whip snap" action causing the screen to be thrown into sharp vibration and resulting in its being freed of material caught within its mesh; and third, the screen returns and is 60 presented to the falling material at an angle expediting the passage of the particles of material of proper size through the screen.

A still further object is the provision of 65 means whereby the degree of inclination of the screen may be quickly and conveniently altered.

My invention further contemplates a cascade arrangement of a series of screens of 70 varying meshes, preferably all acting under the influence of the same actuating medium, the demand upon the actuating medium being apportioned so as to be made practically continuous and even; the preferred embodiment utilizing electromagnetic means for 75 vibrating the individual screens, all of such means receiving current from a common source, the flow of current being controlled by a contact device common to all and wherein the contacts are arranged to obviate flashing, and to obtain the aforesaid evenness of 80 demand upon the current.

Embodiments of my invention wherein the above objects are attained, are illustrated in the drawings accompanying and forming 85 a part hereof and wherein similar reference characters are used to designate corresponding parts throughout the several views.

Figure 1 is a front elevation, and Fig. 2 a side elevation of a single screen separating 90 apparatus embodying my invention; Fig. 3 is a section on the line 3—3 of Fig. 2; Fig. 4 is a perspective view of one of the screen suspension springs and its holder, and includes fragments of the screen and trough; 95 Figs. 5, 6, and 7 are conventional illustrations of three successive steps or conditions in the screen action; and Fig. 8 is a diagrammatic representation of a cascade arrangement of a series of screens, with their actuating means.

Turning first to the structural details of

the embodiment of my invention illustrated particularly in Figs. 1 to 4, 1 represents a screen frame that is supported by means presently to be described from a structure 5 comprising, in the present instance, horizontal members 2 and vertical members 3 between the latter of which is pivoted, near their upper ends, one end of a trough 5, the opposite end of the trough being adjustably 10 supported, through links 6, from the forward ends of the members 2. The upper ends of the links 6 are clamped to the trough by means, such as bolts 7, while the lower ends of the links are pivotally connected to 15 the members 2, at 8.

A feed box 10, containing a screw conveyer 11, is supported by the upper ends of the members 3 in a position to discharge onto the upper end of the screen, the bottom of 20 the feed box comprising a stationary plate 12 and a hinged feed plate 13 the free edge of which is normally supported by the stops 14.

The screen frame is made up of side members which are connected at their upper ends by a member 16, and, at suitable distances therealong, by bars 17 which are spaced above the surface of the screen 18 a sufficient distance to allow free passage of the material beneath them. The screen 18 may consist of a sheet of suitable cloth or wire gauze and has its edges connected to the underneath surfaces of the frame in any approved manner.

Spring saddles 20 are connected to the sides of the frame 1 and are arranged to ride the upper ends of leaf springs 22 that are adjustably supported by holders 23, said holders being in the form of blocks having 35 vertical passage ways for the spring. The springs are clamped within the holders by wedges 24, and these wedges are in turn held in place by set-screws 25. While the stiffness of the springs may be altered within a 40 limited range by the adjustment of the springs vertically within the holders without changing the elevation of the screen frame to any great extent, yet I may include means of adjusting the tension of the springs which 45 will have no effect on the position of the screen, such means consisting of a plate 27 which fits within the passage way of each spring holder along side the spring and has its upper end slidably connected to the 50 spring by a plate 28. It is apparent that by sliding the plate 27 vertically within the holder the stiffness of the spring may be altered without affecting its relative position to the holder. The engaging parts of the 55 spring saddles and springs are shaped to afford practically a knife edge or line bearing between the saddles and springs, and are made of sufficient hardness to effectually resist wear. The spring holders are shown as 60 provided each with a threaded stud 30 which

extends through an aperture 31 in the side of the trough 5 and has applied to it beyond such side a nut 32 for clamping the spring holder in any adjusted position to the side of the trough. This adjustment is essential 70 in that it allows the springs to be arranged vertically regardless of the inclination of the trough 5, so that the frame will swing with equal ease each side of its center of vibration. Any required number of springs may 75 be employed on each side of the apparatus, depending upon the size and weight of the screen frame and material to be treated, two being shown on each side of the apparatus herein disclosed.

An electromagnet 35 is shown as located on each side of the apparatus, the same being carried by an arm 36 which is pivoted at 37 to the side of the trough 5, the pivotal connection being of such nature as to allow 85 the magnet to be secured in various adjusted positions. An armature 40 is supported in operative relation to the face of each magnet from the adjacent side of the screen frame, the connection between the armature and frame allowing an adjustment to compensate for the adjustment of the magnet.

The electromagnets 35 may receive current from any suitable source, and unless the current is alternating and of a frequency which 90 will result in the desired timing of the vibrations of the screen (as the magnets attract and release their armatures) or such as to produce pulsations substantially in step with the synchronism of the screen supporting springs, the current must be intermittently interrupted for the attainment of these desired ends by a suitable contact device or "flasher." Such a device is herein illustrated conventionally as a rotor 42 having one or more contact points 43 that are engaged by a brush 44 through which current is led from one side of the circuit, represented by the wire 45, through the conductive portion of the rotor to a brush 46 and 100 wire 47 to one end of the windings of the electromagnets, the opposite ends of the windings having connection to the opposite side of the circuit represented by the wire 48. The rotor is shown as mounted upon 105 the shaft 50 of an electric motor 51. A switch 52 is included in the circuit for opening the circuit at any time it is desired to stop the operation of the apparatus, and variable resistance 53 may also be included 110 in the circuit for changing the strength of current so as to vary the violence of vibration of the screen, such an adjustment being advantageous in handling materials of various weights.

A controller or rheostat 54 may be included in the motor circuit to change the speed of the motor, and consequently that of the rotor, so that the frequency of the current interruptions may be varied at will.

To restrict the vibrations of the screen to a well defined limit, when such is desired, I employ adjustable stops 55, carried by a bracket 56, one of which is shown as adjustably connected at 57 to each side of the trough 5; and a finger 58, similarly connected to the adjacent side of the screen frame, extends downward between the stops for engagement therewith.

10 Adjustable tappets 60 are supported, through brackets 61, from the upper end member 16 of the screen frame in a position to strike the free edge portion of the feed plate 13 when the frame is vibrated, thereby 15 to insure constant feeding of material while the apparatus is operating.

The screened material caught by the trough 5 is delivered to a hopper 65 from where it is conveyed through a chute 66 to 20 a suitable bin or storage, and the tailings discharged from the lower end of the screen frame are caught by a hopper 67 and may be returned, through a chute 68, to the grinder or to a place where they may accumulate for further grinding.

In Figs. 5, 6, and 7, I have endeavored to illustrate the action of the screen. In the first of these figures the screen is shown at rest and the flow of material is due to gravity and the inclination of the screen. In this case, the separation is but little as the "fines"—or those particles which are small enough to pass through the mesh of the screen—are so intermixed with the coarser particles that but few of them come in contact with the screen and pass through. When the magnets are energized the screen is suddenly drawn away from the material in a substantially horizontal direction, leaving the material in the air, the particles thereof dropping according to weight and inertia. Now that the screen surface is free of material, and the travel of the screen in its present direction of movement is suddenly arrested either by the engagement of the fingers 58 with the appropriate stops 55, or the engagement of the armatures 40 with the magnets, the suddenness of the stopping throws the screen into sharp vibration resulting in its being entirely freed of any material which may have been caught within its mesh, and rendering it clean to receive its subsequent shower of material. Upon the deenergization of the magnets, the screen is allowed to move in the opposite direction at an angle to the falling material, the particles of which have become separated and loosened during their brief suspension in the air, and the openings of the screen are presented to the particles of material at an angle affording the best possible chance for the sufficiently small particles to pass through the screen. At the extreme end of the present movement of the screen the stop 60 is less abrupt than before, due to the cushioning effect of the springs and the fact that the screen is merely passive, wherefore only a comparatively light shock is imparted to the screen which serves to free it of any lightly held material.

70

By timing the frequency of the current impulses with respect to the spring strengths and adjustments and the weights of material and inertia of the screen frame, a synchronization can be secured that will give perfect results for any particular sort of material.

Almost any degree of movement and rapidity of vibration can be obtained by adjusting the stops and increasing or decreasing the frequency of the current pulsations; and the importance of such a range of adjustment will be better appreciated and it is said that some materials separate best at low rates of vibration, while others respond 85 with efficiency only to very rapid short strokes. Also very gentle or very powerful action can be obtained through the variations in the strength of current attainable through the variable resistance above referred to.

80

In cases where it is desired to separate the material into various grades, I provide an installation diagrammatically illustrated in Fig. 8 where a series of screens are arranged 95 to successively receive the material, the first screen being of a mesh to permit the passage of the coarsest material to be graded, the remainder being recovered for regrinding. This first screen is known as the 100 "scalping" screen and the material which passes through it is conducted by a trough to the upper end of a screen having the finest mesh of any within the series. Thus the finest grade of material is selected by this 105 screen. The tailings from this second screen are discharged upon the next coarser screen, and the second grade of material passes through this screen, while its tailings are discharged upon a still coarser screen 110 through which the third grade of material passes, etc.

115

Referring more specifically to the diagram by the use of reference characters, 1^a represents the upper or "scalping" screen, and 5^a the trough which receives its products and discharges them upon the finest screen 1^b, the next coarser screen being represented by 1^c and the next by 1^d. A conveyer trough 70 receives the tailings from the first or "scalping" screen and discharges them into a chute 71 which conducts the material back to a place for regrinding. The other successive screens of the series drop their material into the respective bins 72, 73, and 74, the last 125 screen, or the one designated 1^d, discharging its tailings into the bin 75. For example, it will be assumed that screen 1^a is of 16 mesh; screen 1^b is of 90 mesh; screen 1^c of 60 mesh, and screen 1^d, 30 mesh. Consequently, 130

bin 72 will receive material known as "90 mesh and up"; bin 73 will receive material of from 60 to 90 mesh; bin 74, 30 to 60 mesh, and bin 75, 16 to 30 mesh.

- 5 In the cascade arrangement of the screens the magnets of the various screens receive their current from a common source represented by the battery 80, and the circuits involving the various magnets are controlled 10 by a contact device represented by the drum 81 that is driven by motor 82. The drum is shown as of conductive material with inserts 83 of insulating material over which brushes 84 ride. A brush 85, constituting 15 the terminal of the wire 86 from the battery, maintains permanent contact with the conductive portion of the drum 81. The inserts are so arranged that the circuit is never completely interrupted, thus obviating "flashing" 20 at the contact points of the brushes, and so as to make the demand upon the current practically continuous.

In a practical installation of the apparatus, the motor and contact device may be located 25 at some point remote from the screens and properly housed to protect them from the dust and dirt prevalent in the vicinity of the screens. The switches 88, however, are located within easy reach of the screen 30 attendants so that any one or more of the screens may be stopped at will.

The easy removability of the individual screens is deemed highly desirable, for it greatly facilitates repair and, if desired, 35 substitute screens may be kept on hand to replace any withdrawn from service for the purpose of repair, the suspension means for the screen frames being so simple as to readily permit of such interchangeability.

40 While I have shown a magnet located on each side of the screen, it will be understood that this arrangement need not be adhered to. If the work is sufficiently light, one magnet located on one side of the apparatus 45 would be ample to obtain a comparatively even pull on the screen frame; or the magnet and armature might be located at any other convenient part of the apparatus for obtaining an even pull, such an expedient being so obvious that specific illustration is 50 deemed unnecessary.

Having thus described my invention, what I claim is:—

1. In apparatus of the character set forth, 55 the combination of a spring holder having a passageway, a leaf spring, a spring stiffener, a wedge for securing portions of the spring and spring stiffener within the passageway of the holder, and a screen supported by the 60 spring.

2. In apparatus of the character set forth, 65 the combination of a spring holder having a passageway, a leaf spring, a spring stiffener,

a wedge for securing portions of the spring and spring stiffener within the passageway 65 of the holder, retaining means for the wedge, and a screen supported by the spring.

3. In apparatus of the character set forth, the combination of a plurality of movable screens, an armature and an electromagnet 70 for each screen, one being carried by the screen and the other arranged in operative relation to the one carried by the screen, a source of electric energy, circuits including 75 said source and the electromagnets, and a contact device for opening and closing the various circuits alternately whereby a comparatively even flow of current is obtained.

4. In apparatus of the character set forth, the combination of a supporting structure 80 having a receiving surface, a sub-structure whereby the supporting structure is adapted to be sustained at various angles, resilient screen supporting elements adjustably carried by the supporting structure so as to be 85 substantially vertically disposed when the supporting structure is in any of its positions, and a screen having bearing members resting upon the screen supporting elements.

5. In apparatus of the character set forth, 90 the combination of a supporting structure, a sub-structure wherein the supporting structure is adapted to be sustained in various inclined positions, resilient screen supporting 95 elements carried by the supporting structure and adjustable with respect thereto so that they may be vertically disposed while the supporting structure is in any of its inclined positions, a screen having bearing members resting upon the screen supporting elements, and cooperating stops carried respectively 100 by the screen and supporting structure and adjustable with respect thereto to compensate for the various inclined positions of the supporting structure.

6. In apparatus of the character set forth, the combination of spring holders each having a vertically disposed passageway, a leaf-spring adjustable within the passageway, a spring stiffener adjustable within the passageway and slidably connected at its upper 110 end with the spring, means for securing the spring and spring stiffener at any adjusted position within the holder, and a screen having bearing members arranged to rest upon 115 the springs.

7. In apparatus of the character set forth, the combination of a supporting structure, a sub-structure wherein the supporting structure is adapted to be sustained at varying degrees of inclination, screen supporting elements adjustably carried by the supporting structure and adapted to be substantially vertically disposed at all times, a screen having bearing members resting upon the supporting elements, the supporting elements 125

yielding to a vibratory movement of the screen, an electromagnet adjustably carried by the supporting structure, and an armature disposed in operative relation thereto and carried by the screen, the armature being adjustable to compensate for the adjustment of the magnet.

In testimony whereof, I hereunto affix my signature in the presence of two witnesses.

CHARLES C. RUPRECHT.
